(57) **CLAIM**

The ornamental design for a base for a base of a table, as shown and described.

DESCRIPTION

FIG. 1 is a front perspective view of a base for a table showing the new design;

FIG. 2 is a front elevation view thereof;

FIG. 3 is a back elevation view thereof;

FIG. 4 is a top plan view thereof;

FIG. 5 is a bottom plan view thereof;

FIG. 6 is a right elevation view thereof;

FIG. 7 is a left elevation view thereof;

FIG. 8 is a front perspective view of a second embodiment of a base for a table showing the new design;

FIG. 9 is a front elevation view thereof;

FIG. 10 is a back elevation view thereof;

FIG. 11 is a top plan view thereof;

FIG. 12 is a bottom plan view thereof;

FIG. 13 is a right elevation view thereof; and,

FIG. 14 is a left elevation view thereof.

The broken lines in the drawings are for illustrating portions of the article that form no part of the claimed design.

The base for a table is shown with symbolic breaks in its legs. The appearance of any portion of the article between the break lines forms no part of the claimed design. The break lines themselves are for illustrating the breakaway and form no part of the claimed design.
